FOLDING TABLE

Carl Lewis Noelcke, Sr., Cincinnati, Ohio

Application July 7, 1937, Serial No. 152,395

3 Claims. (Cl. 311—78)

This invention relates to folding tables and more particularly to readily portable and collapsible tables for use in packing parachutes in the field. It is a general practice to fold a parachute and pack it immediately after the descent is complete and without removing the parachute to a workshop or hangar. This is thought to be a safety precaution in that there is no chance of getting any of the lines fouled in returning the 10 parachute unpacked from the field.

It is a difficult matter to fold a parachute on the ground particularly in a field, because there is always danger of packing in twigs and dirt, or perhaps stones which might cause damage to the 15 parachute. As far as I am aware, there has never been provided a convenient table upon which a parachute may be folded, and it is therefore an object of my invention to provide such a table which may speedily be erected anywhere in the field and which will then provide a 20 convenient table upon which a parachute may be folded and packed. It is another object of my invention to provide a table as above outlined, which will be relatively cheap to manufacture and simple to erect.

These and other objects of my invention which will be described hereinafter or which will be apparent to one skilled in the art upon reading this 30 specification, I accomplish by that certain construction and arrangement of parts of which I shall now describe an exemplary embodiment. Reference is now made to the drawing forming a part hereof, and in which:

Figure 1 is a plan view with parts broken away, 35 of a table according to my invention.

Fig. 2 is a cross sectional view of the same taken on the line 2—2 of Fig. 1.

Fig. 3 is a cross sectional view of the same taken along the line 3—3 of Fig. 1.

Fig. 4 is a detailed perspective view of the 40 grommets and cords for tying down certain parts of the parachute.

Fig. 5 is a perspective view of the table of Fig. 1 in erected form ready for use.

Fig. 6 is a side elevation of a table of a somewhat modified form.

Briefly in the practice of my invention, I provide a long, narrow strip of canvas and means for supporting the strip at a convenient height 50 and for reenforcing it in certain points.

Referring more particularly to the drawing in which like reference numerals indicate like parts in the different figures, I have indicated the strip of canvas forming the table at 10. I have found 55 that for most purposes this strip should be some

42 ft. long. Sewn to the under side of the member 10 are the longitudinal tape members 11 which are sewn along the edges of the table and the strips 12 which are sewn longitudinally between the strips 11. One of the tapes 11 is preferably provided at each end with a D-ring 13 and the other tape 11 is preferably provided at each end with a snap hook 14. In this way the table may be supported as shown in Fig. 5, by passing the tapes 11 around a tree and buckled 10 at one end, passing the tapes at the other end around, for example, the spare tire of an automobile and buckling them. The automobile may then be slowly driven away from the tree until the member 10 is taut. It is to be understood, 15 of course, that the table may be stretched between two automobiles if desired. At each end of the table I provide a wooden cross bar 15 and pass the member 10 around the same as shown most clearly in Fig. 2. This serves to maintain 20 the table in transversely distended condition. Intermediate the ends of the table I preferably provide two transverse supporting boards 16 which may be spaced approximately at locations $\frac{1}{3}$ and $\frac{2}{3}$ respectively the length of the table. 25 The members 16 are held in place by auxiliary strips of material passing underneath them as at 17 and sewed to the member 10. I prefer to drill holes 18 in the members 16 and provide leg members 19 having reduced ends 20 adapted to 30 seat within the holes 18.

At one end of the table I provide a tool pocket formed by a flap of material indicated at 21, fastened to the member 10 and preferably also the tapes 11 and 12 by some fastening means 35 which are indicated generally at 22. At its free end the member 21 may be provided with snap member 23 and the member 21 is sewed to the member 10 along its edges as indicated at 24 in Fig. 2. 40

At the opposite end of the table I provide a snap hook 25 which may be fastened in a loop of material as at 26 to the member 10 and toward the other end of the table I provide at the points indicated by the numeral 27 tying members 45 which are shown in more detail in Fig. 4. These comprise each a pair of grommets 28 through which is passed a cord or tape 29 preferably tied up above the grommets as at 30.

In the underside of the member 10 I may provide 50 pockets for the leg members 19, as shown at 33. These may take the form of a strip of canvas or the like, looped and stitched to the member 10 as at 34. Thus I may provide space for two legs adjacent each of the members 16, and ad- 55

jacent the members 16a in the modification of Fig. 6.

In use, the tapes 11 at one end of the table are passed about the tree as indicated at 31 in Fig. 5 and buckled. The tapes at the other end are fastened, for example, around the spare tire 32 and buckled at the other end, and the automobile is driven in the direction of the arrow until the member 10 is taut. The leg members 10 are then inserted in the bores 20 in the boards 16 and the table is then ready for use.

In Fig. 6 I have shown a slightly modified table in which instead of the bars 15 at the two ends of the table there are provided additional boards 16a in all respects similar to the boards 16 above described, and there are provided auxiliary leg members 19a to act with the boards 16a. Instead of the tapes 11 and buckles 13 and 14, I provide the ropes 11a provided with cleats 12a which are used in a conventional manner with the tent pegs 31. It will thus be seen that the only difference between the table of Fig. 6 and the table of Fig. 5 is in the manner of erecting it. In the case of the table of Fig. 6 it will be necessary to insert the leg members 19 and 19a at appropriate places and then extend the table until it is taut, by exerting tension on the ropes 11a and holding the ropes taut by means of the cleats 12a. When it is desired to pack a parachute on my novel table, the apex thereof is attached to the snap member 25 and the parachute is laid out on the table with the harness portion toward the other end of the table. The harness is preferably tied to the table by means of the tapes 27 at the left hand end of the table and the tapes 27 at the middle of the table may serve to tie the parachute rims in place. With this table and with the conventional parachute on the market today, the skirt portion of the parachute will extend approximately to the board 16 near the right hand end of the table and the folding of the parachute is actually done using the board 16 as a supporting surface.

It will be noted that my table is also convenient if it is desired to pack several parachutes immediately in succession. In the event that when the first parachute is packed for duty it is desired to have the pack pulled together, the rip cord put in place, and the final operations of parachute packing performed, it may be moved toward the left to rest upon the other board 16 and in the meantime a successive parachute may be laid out on the first board 16.

It is to be understood that dimensions given herein are exemplary only and that many modifications can be made for example in the construction of the legs 19 and 19a and in the particular manner of fastening the tapes and hooks and the like without departing from the spirit of my invention; and I therefore do not intend to limit myself other than as pointed out in the claims which follow.

Having thus described my invention, what I claim as new and desire to secure by Letters Patent is:

1. A table for the purposes described comprising a relatively long, narrow strip of flexible material, fastening means at each end of said strip 15 whereby it may be maintained in taut condition, means to cause said strip to maintain a transversely distended condition, and intermediate supporting means between the ends of said strip, said supporting means comprising relatively stiff 20 members fastened to said strip and provided with legs, said supporting means being disposed to divide said table into three approximately equal lengths.

2. A table for the purposes described comprising a relatively long, narrow strip of flexible material, said strip at its two ends passing around and retaining transversely disposed distending members, relatively stiff supporting elements attached to said table transversely and spaced to 30 divide said table into three approximately equal parts, tapes sewed to said table longitudinally thereof along the edges of said table and extending therebeyond and provided with fastening means on their ends, leg members to cooperate 35 with said supporting elements, a hook member attached to said table at one end thereof and tying members attached to said table near the other end thereof.

3. A parachute packing table comprising a relatively long, narrow strip of flexible material, transversely disposed distending members fastened thereto, two of said members being disposed at the respective ends of said table and two of said members being disposed intermediate the 45 ends and spaced to divide said table into three approximately equal parts, detachable leg members coacting with each of said distending members, and means at each end of said table for exerting tension thereon. 50

CARL LEWIS NOELCKE, SR.
